COMBINED GUIDE AND HOLDER FOR FACILITATING THE PLACEMENT OF CONTACT LENS ON THE CORNEA OF THE EYE

Charles H. Kolbeck, Milwaukee, Wis., assignor to Vue Optical Products, Inc., Milwaukee, Wis., a corporation

Filed Feb. 1, 1963, Ser. No. 73,398

Term of patent 14 years

(Cl. D57—1)

Fig. 1

Fig. 2

Fig. 3

Fig. 4

Fig. 5

FIGURE 1 is a perspective view of a combined guide and holder for facilitating the placement of contact lens on the cornea of the eye embodying my new design;

FIGURE 2 is a top plan view thereof;

FIGURE 3 is a side elevational view thereof;

FIGURE 4 is an end elevation as seen from the right side of FIGURE 2, and

FIGURE 5 is an end elevational view thereof as seen from the left of FIGURE 2.

I claim:

The ornamental design for a combined guide and holder for facilitating the placement of contact lens on the cornea of the eye, substantially as shown.
